[57] CLAIM

The ornamental design for a welding outlet, as shown.

DESCRIPTION

FIG. 1 is a side elevational view of a welding outlet, showing my new design;

FIG. 2 is another side elevational view taken 90° from the side shown in FIG. 1;

FIG. 3 is a top plan view thereof;

FIG. 4 is an isometric view thereof; and,

FIG. 5 is a bottom plan view thereof.

FIG. 1

FIG. 4

FIG. 2

FIG. 3

FIG. 5
